OTTO H. MERZ, OF WEST ALLIS, WISCONSIN

FASTENING MEANS

Application filed January 20, 1927. Serial No. 162,222.

My invention relates to fastening means which may be adapted for general use but which is designed particularly for use in combination storm and screen doors for detachably fastening either the glazed or screened closure in the door frame or casing. The invention may be said to cover improvements and additions in the fastening means disclosed in Patent No. 1,570,072 issued January 19th, 1926.

The important feature of improvement is the efficient securing of the fastener independently of nails or screws and by means which automatically function when the fastener is inserted into its seating channel or pocket on one of the frame parts to be secured together.

Referring to the drawings:

Figure 1 is an elevational view of the corner of a door frame and closure insert secured therein by means of my improved fastening means;

Fig. 2 is a sectional view on plane 2—2 of Fig. 1;

Fig. 3 is a side elevational view of the fastening mechanism;

Fig. 4 is an end view; and

Fig. 5 is a bottom side view.

I have shown the fastening mechanism applied to a door frame 10 for fastening in the opening 11 of such frame a closure 12 which may be either glazed or screened. The door frame has the weather ledge 13 along one edge surrounding the opening 11, while the closure frame or insert 12 has the ledge 14 along the opposite edge, the insert engaging against the ledge 13 and the ledge 14 engaging against the door frame when the insert is in the opening 11 to thus form a weather-tight fit.

The fastening structure comprises a frame or body 15 and a fastening or latch bar 16. The body is formed from a single piece of sheet metal which is depressed to provide a longitudinally extending guide groove 17 and

the surrounding flange 18, the inner end of the groove and flange being semi-circular. The longitudinal walls of the groove 17 are deflected to form the dove-tail sides 19 and 20, and the door frame is routed out with a dove-tail bit to form the dove-tail channel 21 for receiving the dove-tail sided body 15. Such dove-tail joints assist materially in holding the fastening structure in its channel with its flange against the face of the door frame, the fastener structure frame being readily insertible longitudinally into the supporting channel.

The fastening or latch bar 16 which is stamped integral of sheet metal has the dove-tailed sides 22 and 23 which fit and cooperate with the inner faces of the dove-tailed side walls 19 and 20 of the body 15. The outer end 16' of the fastening bar is deflected upwardly a trifle in order to provide the beveled under surface 24. The inner end of the fastening bar is deflected upwardly to form the abutment 25 by means of which the bar may be readily slid to its inner or outer position. For preventing accidental removal of the fastening bar from its supporting frame and also to gauge the outward and inward movement of the bar, a detent hump or abutment 26 is deflected from the bottom wall of the groove 17 to extend into the longitudinal slot 27 in the bar, the abutment then cooperating with the ends of the slot to limit the outward or inward movement of the bar.

In the bottom wall of the groove 17 is the opening 28 for the leaf spring 29 which is secured to such bottom wall behind the opening as by means of a rivet 30. The front part of the spring extends along the opening 28 and its front end has the upward deflection 31 which presses against the underside of the fastening bar to thus frictionally hold the bar in any intermediate position into which it may be moved. When the bar is entirely out with its slot 27 engaging the abutment projection 26, the spring end 31 will be be-

hind the rounded corner 25' of the bar at the base of its extension 25, such engagement of the spring being a distance above the lower face of the bar so that the bar will be yieldingly held in its outer position but may be returned inwardly by exertion of pressure against the bar end. The spring opposes inward movement of the bar sufficiently so that when the fastening structure is in use the bar 10 will be retained in its outer position and cannot accidentally work its way inwardly.

The inner end 32 of the spring extends a distance beyond the rivet 30 and is pointed as indicated at 33 (Fig. 5) so that the spring 15 end may readily pass into the wood behind the channel 21 when the fastening structure is inserted therein, and preferably the spring end is slanted downwardly so that when it is forced into the wood it will draw the rear 20 end of the fastener body to firmly seat it in its receiving channel and with its flange 18 intimately against the face of the supporting framework.

At its front end the bottom wall of the 25 groove 17 has integral therewith the extension comprising the wall section 34 extending downwardly at substantially right angles with the groove bottom, and the wood entering point or wall section 35 extending inwardly substantially parallel with the groove bottom. When the fastener mechanism is inserted in its supporting channel 21 the point 35 will be driven into the wood of the supporting framework, and in order to cause the 30 fastener structure body to be drawn intimately to the supporting framework, the point 35 is given a slight downward slant, and the wall 34 may also slant forwardly a trifle so that when this fastening extension is driven 35 with a hammer the point will draw downwardly on the wall 34 so that the body of the fastening structure is drawn firmly against the surface of the supporting framework. During such driving of the point the wall 40 34 will be bent so as to engage firmly against the side edge of the frame to which the structure is applied. The point 35 together with the spring end 33 will thus securely and intimately hold the fastener structure body in 45 its operative position on the supporting framework, and the use of screws, nails or extra securing devices will be eliminated.

In Figs. 1 and 2 the application and operation of the fastening structure is illustrated. 50 The fasteners are applied to the supporting frame 10 to extend at right angles with the closure receiving opening 11, and for receiving the projected fastening bars the inserted frame 12 has the kerfs or recesses 36 formed 55 therein, and the beveled under-surfaces 24 of the fastening bars engage against the inner sides of the kerfs in order to clamp the inserted frame to the door frame with weather-tight engagement.

60 The dove-tail joint connection between the

fastening structure body and the supporting frame need not be depended upon to hold the body in place as the spring end 33 and the point 35 will be mainly depended upon to secure the structure, and as the spring and point are inaccessible when an insert frame is in place in the supporting frame, it will be impossible to remove the fastening structure. The pressure of the spring 29 against the underside of the fastening bar will prevent rattling of the bar and release movement of the bar until sufficient positive pressure is exerted against the bar projection 25. No amount of rattling, jarring or jolting of the door can therefore dislodge the fastening bar from 70 locking position.

Having described my invention I claim as follows:

1. A fastening device for the purpose described comprising a body part having a longitudinally extending groove, a fastening bar 85 slideable in said groove and having interfitting engagement at its sides with the groove sides, a spring secured to said body and extending at one end into said groove and against said fastening bar to yieldingly lock said bar in adjusted position, the other end of the spring being extended to form a wood engaging point, and an extension at the front end of said groove forming a rearwardly extending 90 wood engaging point below said body.

2. In combination, a support having a surface channel extending therein from a side edge thereof, a fastening device comprising a body part of sheet metal having a longitudinally deflected part for sliding into and engaging in said channel, said deflected part forming a groove, a fastening bar slideable in the groove, a point extending rearwardly from the rear end of the deflected part for entering the material of the support when the body part is slid into said channel, a wall 100 extending downwardly from the front end of said deflected part and a point extending rearwardly from the lower end of said wall, said wall engaging against said support side when the body part is slid into the channel and the point on said wall entering the material of the support, said points serving to secure said body part in said channel against 105 displacement thereof at right angles with said support.

3. A fastening device for the purpose described comprising a body formed integral of sheet metal and having a longitudinal deflection for engaging in a supporting channel and forming a groove, a fastening bar slideable in the groove and confined therein, a spring secured intermediate its ends to the bottom and at the rear of said body, the front end of said spring engaging said fastening bar to yieldingly hold it in adjusted position, the rear end of said spring extending rearwardly beyond said body to form an anchoring point, a wall integral with said body de- 115 120 125 130

pending from the front end of said groove, and a rearward extension on said wall forming an anchoring point, said point being normally slightly divergent from said body part 5 whereby when said body part is applied in the supporting channel said point will be driven into the material surrounding the channel to draw said body part downwardly in said channel.

10 In witness whereof, I hereunto subscribe my name this 15th day of January, 1927.

OTTO H. MERZ.
